(57) **CLAIM**

The ornamental design for the refrigerator cabinet door lock as shown and described.

DESCRIPTION

FIG. 1 is a perspective of a refrigerator cabinet door lock; FIG. 2 is a front view thereof; FIG. 3 is a back view thereof; FIG. 4 is a left side view thereof; FIG. 5 is a top view thereof; FIG. 6 is a bottom view thereof; FIG. 7 is an enlarged perspective of another embodiment of a refrigerator cabinet door lock; FIG. 8 is a front view thereof; FIG. 9 is a back view thereof; FIG. 10 is a left side view thereof; FIG. 11 is a top view thereof; and, FIG. 12 is a bottom view thereof.

The left side view forms no part of the embodiments of the claimed design shown in FIGS. 1-6.

The right side view forms no part of the embodiments of the claimed design shown in FIGS. 7-12

Elements shown in broken line form no part of the claimed design.

1 Claim, 12 Drawing Sheets
